Specification of Letters Patent.

Patented May 30, 1911.

Application filed August 19, 1910. Serial No. 578,044.

To all whom it may concern:

Be it known that I, FRANCESCO SARTORI, a subject of the King of Italy, residing at Monteponi, Sardinia, Italy, have invented a certain new and useful Improved Electric Furnace, of which the following is a specification.

This invention relates to a type of electric resistance furnace in which the muffle intended to contain the material to be treated, is closed at one of its ends and mounted so as to be able to assume the vertical position with the open end facing upward when it is desired to introduce a charge, a horizontal or almost horizontal position during the treatment, and the vertical position with the opening downward, for discharging the material.

A construction of the furnace according to this invention, specially adapted for the treatment of zinc ores, is illustrated by way of example in the accompanying drawing.

As shown on the drawing, the muffle has a shape similar to that of the muffles used in zinc metallurgy, but it is formed of a refractory material which is a bad conductor of electricity, such as refractory mixtures of clay, coke or graphite, so that it is possible to heat it up to 1200-1300° C. by an electric current supplied by electrodes 2, 2. The muffle 1 is arranged in a cylindrical sheet metal receptacle 3 closed at one end, and between the wall of the muffle 1 and the sheet metal receptacle, there is a refractory lining 5 formed of several layers of non-conducting material 6 or air chambers.

The sheet metal receptacle 3 with its refractory lining can be extended, at its open end beyond the mouth of the muffle, either around the whole circumference, or only partly around the circumference, such as the portion 4 projecting beyond the mouth of the muffle and provided with a movable cover 11. In any case, the receptacle 3 is provided with pivot pins 7 mounted on bearings 8, so as to be able to rotate thereon. By means of a worm wheel secured to one of the said pivots 7, and of a worm mounted on the corresponding bracket or bearing 8, or in any other suitable manner, the rotation of the furnace can be easily effected.

The charging of the furnace is effected by bringing it into the vertical position with the open end upward and by introducing into the hopper 9 the material to be treated, such as calcined calamine, roasted blonde or other ores or by-products mixed with poor coal. When the charging is completed, the receptacle is brought into practically a horizontal position, and a condenser is applied to the mouth of the muffle for collecting the zinc. Finally, the cover 11 is put on and thus forms a hot chamber around the condenser. A plate 12 of refractory material supports the front portion of the condenser and prevents radiation. It is preferable to provide the condenser with an extension 13. When the process is completed, the cover 11, the condenser 10 and the plate 12 are removed, whereupon, by means of the worm, the furnace is brought into the vertical position with the open end downward, and the residues of the distillation are discharged through an opening 14 provided below the apparatus.

What I claim as my invention and desire to secure by Letters Patent is:—

1. In an electric furnace for the distillation of zinc from its ores or by-products, the combination of a muffle closed at one end and made of refractory material which is a bad electric conductor, a vessel closed at one end to contain the muffle and pivoted so that it can be rotated about a horizontal axis and adapted to extend at its open end beyond the mouth of the muffle, a condenser for zinc adapted to be connected to the mouth of the muffle and to extend beyond the open end of the vessel, and a member to close the mouth of the vessel and having an opening through which the condenser can pass for the purpose set forth.

2. In an electric furnace for the distillation of zinc from its ores or by-products, the combination of a muffle closed at one end and made of refractory material which is a bad electric conductor, a vessel closed at one end to contain the muffle and pivoted so that it can be rotated about a horizontal axis and adapted to extend a segment of its circumference at its open end beyond the mouth of the muffle, a cover to complete the unex-

tended segment of its circumference, a condenser for zinc adapted to be connected to the mouth of the muffle and to extend beyond the open end of the vessel, and a member to close the mouth of the vessel and having an opening through which the condenser can pass for the purpose set forth.

In testimony whereof I have signed my name to this specification in the presence of two subscribing witnesses.

FRANCESCO SARTORI.
